CLAIM

The ornamental design for a boot, as shown and described.

DESCRIPTION

FIG. 1 is a perspective view of a boot according to our new design;

FIG. 2 is a front view of the boot of FIG. 1;

FIG. 3 is a back view of the boot of FIG. 1;

FIG. 4 is a top view of the boot of FIG. 1;

FIG. 5 is a left side view of the boot of FIG. 1; and,
FIG. 6 is a right side view of the boot of FIG. 1.

The broken lines in the drawings are not part of the claimed
design.
